[57] CLAIM

The ornamental design for a CD disc display holder, as shown and described.

DESCRIPTION

FIG. 1 is a perspective view of a CD disc display holder embodying my new design;

FIG. 2 is a front elevational view thereof, the rear elevational view being a mirror image thereof;

FIG. 3 is a side elevational view of one side thereof, the opposite side being a mirror image thereof;

FIG. 4 is a top plan view thereof;

FIG. 5 is a bottom plan view thereof;

FIG. 6 is a perspective view of a second alternative embodiment thereof.

FIG. 7 is a front elevational view of the embodiment illustrated in FIG. 6;

FIG. 8 is a rear elevational view of the embodiment of FIG. 6;

FIG. 9 is a side elevational view of the embodiment of FIG. 6, the opposite side being a mirror image thereof;

and,

FIG. 10 is a top plan view of the embodiment of FIG. 6.

The bottom plan view of the embodiment of FIG. 6 is identical to the bottom plan view illustrated in FIG. 5.

FIG. 1

FIG. 5

FIG. 2

FIG. 3

FIG. 4

FIG. 6

FIG. 7

FIG. 8

FIG. 9

FIG. 10
